UNITED STATES PATENT OFFICE.

ABRAHAM LINCOLN HENSON, OF FORT COLLINS, COLORADO.

FLYING-MACHINE.

1,104,045.

Specification of Letters Patent. Patented July 21, 1914.

Application filed January 15, 1913. Serial No. 742,255.

To all whom it may concern:

Be it known that I, ABRAHAM LINCOLN HENSON, a citizen of the United States, residing at Fort Collins, in the county of 5 Larimer and State of Colorado, have invented new and useful Improvements in Flying-Machines, of which the following is a specification.

This invention relates to flying machines 10 of the heavier-than-air type, and particularly to those of the polyplane species, the object of the invention being to provide a flying machine having a low center of gravity to secure a pendulum effect, whereby the 15 machine will be inherently balanced, both laterally and longitudinally, when in flight, and also to provide a novel construction and arrangement of supporting surfaces giving greater lifting power and stability, whereby 20 a construction of machine is provided which will be of maximum steadiness in flight and will maintain its balance under all conditions of service.

A further object of the invention is to 25 provide a flying machine of the character specified in which the planes are grouped in a novel manner to secure strength and rigidity of construction, to avoid liability of collapse of the machine in the air, and which 30 embodies novel steering mechanism including a warping plane arranged in advance of the supporting surface and adapted to be operated in conjunction with the vertical rudder to give a proper list or banking tilt 35 to the machine in making a turn in either direction.

The invention consists of the features of construction, combination and arrangement of parts hereinafter fully described and 40 claimed, reference being had to the accompanying drawings, in which:—

Figure 1 is a side elevation of a flying machine embodying my invention. Fig. 2 is a top plan view of the same. Fig. 3 is 45 a sectional front elevation taken on the line 3—3 of Fig. 2. Fig. 4 is a vertical longitudinal section on the line 4—4 of Fig. 2, through a portion of the machine. Fig. 5 is a diagrammatic perspective view showing the steering and controlling elements.

In carrying my invention into practice I provide a suitable frame structure, including a car 1 and a rear or tail extension 2. The car 1 carries suitably cushioned launching and landing wheels 3, and the tail extension 2 carries suitable yielding skids or

fenders 4, for an obvious purpose. The car 1 is substantially boat-shaped, to give a stream line effect, and tapers forwardly and rearwardly from its transverse center, and also curves in a longitudinal direction, its forward or bow portion being curved or inclined upwardly at an angle of from 25° to 45°, while its rear or stern portion inclines upwardly to a similar degree.

Within the stern portion of the car is disposed the aviator's seat 5, and the steering and controlling levers hereinafter described, while in the bow portion of the car is disposed the driving motor 6. The seat 5 is thus inclined to the plane of flight so that the aviator may have a free view ahead, while the motor 6 is inclined for transmitting motion to propellers inclined to the plane of flight, for a purpose hereinafter explained.

Secured to and extending transversely of the car 1, at the extreme portion of the bow thereof, is a horizontal warping plane 7, the wings 8 and 9 of which are adapted to be warped or flexed helicoidally along the planes indicated by the dotted lines in Fig. 2. Pivotaly mounted at the rear end of the tail extension 2 is a horizontal rudder or elevator 10 hinged or pivoted for vertical movement on a horizontal transverse axis. Supports 11 are provided upon the said tail extension in advance of the horizontal rudder for a vertical rudder 12, which is hinged or pivoted thereto to swing laterally in either direction on a vertical axis. Bracket members 13 and 14 project from opposite sides of the vertical rudder and serve the function of crank arms, as hereinafter set forth.

Rigidly fixed to the car 1 at a point in advance of the transverse center thereof, and between such point and the warping plane 7, is a lower supporting plane 15, whose wings 16 and 17 incline upwardly and outwardly at a dihedral angle of about 25°, and also incline rearwardly at an angle of from 25° to 45°. By this arrangement of the wings of the plane 15, an inherent lateral, as well as inherent longitudinal stabilizing effect is secured when the machine is in flight. Arranged above the plane 15 is an upper supporting plane 18, which is longitudinally straight, i. e., straight between its lateral margins, and is of somewhat less length than the plane 15 and connected at its lateral margins to the plane 15 a short distance in-

2
side the lateral margins thereof. The plane 18 is also connected with the car and plane 15 by suitable struts or braces 19, whereby the two planes are rigidly fastened together 5 and to the main frame. Arranged between the lower plane 15 and the said upper plane 18 is a central or intermediate plane 20, which is relatively shorter than the upper plane 18, and has its end portions secured to the lower plane at points between the car and 10 the points of attachment of the upper plane to the lower plane. This intermediate plane is also fastened to the braces or struts 19 and connected with the upper plane by additional braces or struts 21. In addition, the 15 parts of the planes, as well as the parts of the machine, may be connected and braced from each other by stay wires or bracing connections of any of the types in common use. As shown, the warping plane 7 is reinforced from the main planes by braces 22, while the supports 11 for the vertical rudder 12 are reinforced from the main plane by a brace 23, and the main planes in turn are 20 reinforced from the tail extension by braces 24.

In practice, each main or supporting plane is composed of suitable longitudinal bars or spars and connecting ribs, suitably fastened 30 together and provided with a suitable fabric covering. The car and frame of the machine may also be covered with fabric or other suitable material, if desired, to reduce head resistance. It will be observed that the upper plane 18 is arranged mainly in rear of the longitudinal center of the lower plane 15, while the intermediate plane 20 terminates in rear of the foremost portions of the wings of the lower plane and extends in advance of the foremost portion of the upper plane, the planes thus being arranged in stepped but lapping arrangement, by which the center of pressure of the air upon the supporting surface as a whole may vary to 35 a considerable extent without affecting the longitudinal stability of the machine, while under normal conditions the centers of pressure will tend to meet at a common point, thus automatically maintaining longitudinal 40 stability. By this arrangement of the planes, and the action of the air thereon, as well as the dihedral relationship of the wings of the lower plane, any tendency of the machine to tilt unduly upon its longitudinal or transverse axis will be counteracted 45 by the equalizing and stabilizing action of the air upon the planes, by which the equilibrium of the machine is positively, and automatically maintained. Experiments with 50 models dropped from heights have shown that even if the machine should turn upside down, it will automatically right itself within a range of fall not much greater than its length.

55 It will be observed that the car and

weight of the motor, as well as of the load weight carried, are disposed below the main frame and supporting surface and at such a point that these different weights will perform the function of a pendulum operating 70 by gravity to also maintain stability. This, in conjunction with the stabilizing action of the supporting surface, provides a machine which will retain its normal state of equilibrium even when flying in high winds 75 or partially disrupted by accident.

Journalized in bearings upon the wings of the central plane 20 are longitudinally extending shafts 25 carrying propellers 26 arranged to rotate at points in rear of the 80 supporting surface. These shafts are driven by sprocket chains 27 or other suitable gear from the shaft of the motor 6. It will be observed that the parts of the propelling mechanism are inclined to the plane of 85 flight, in such a manner that the propellers give both a driving and sustaining thrust. By this means the lifting capacity of the machine is increased and its stability further promoted without sacrifice of driving 90 speed.

The car supports a rock shaft 28 arranged transversely in front of the aviator's seat 5, and provided with upwardly and downwardly extending crank arms 29 and 30. 95 Loosely mounted on said shaft, for independent fore and aft movement, is a lever 31 coupled by wires or cables 32 and 33, passing over suitable guide pulleys 34 to crank arms 10^a on the elevator or horizontal 100 rudder 10, whereby said rudder may be adjusted to steer the machine vertically in either direction. Fixed to the shaft 28 is a second lever 35 whereby said shaft may be rocked forwardly or rearwardly to actuate 105 the crank arms 29 and 30. Wires or cables 36 and 37 arranged in crossed relation respectively connect said crank arms 29 and 30 with the right and left hand warping surfaces 8 and 9 of the warping plane 7, 110 and similar wires or cables 36' and 37', arranged in crossed relation, respectively connect the crank arm 29 with the right hand crank 13 of the vertical rudder and the crank arm 30 with the crank arm 14 of the 115 vertical rudder. By this construction when the lever 35 is moved forwardly the rudder 12 will be swung to the right to cause the machine to travel in such direction, while at the same time the surface 9 of the warping 120 plane 7 will be warped down to lift the left hand side of the machine to the desired degree for a banking action in turning. On the other hand when the lever 35 is moved rearwardly the rudder 12 will be turned to 125 the left to steer the machine in that direction, while the warping surface 8 of the warping plane 7 will be warped downwardly to lift the machine at the right hand side to the desired degree for the banking 130

action. The plane 7 is provided for use in conjunction with the vertical rudder in the manner described in order that the automatic stabilizing action of the planes may be 5 temporarily overcome when it is necessary to turn the machine horizontally in one direction or the other and to give it the necessary degree of lateral list or tilt for the required banking action.

10 From the foregoing description, taken in connection with the drawings, the construction and mode of operation of my improved flying machine will be readily understood, and it will be seen that a type of machine is 15 provided which is inherently stable, both longitudinally and laterally to a high degree, and which will thus maintain its balance under adverse conditions. It will also be seen that the invention provides a machine which has great lifting power and 20 speed, and which may be easily and sensitively controlled in flight.

I claim:—

1. In a flying machine, a supporting surface comprising a lower plane having wings angled upwardly and outwardly and rearwardly, an upper plane extending between and secured to the wings of the lower plane and arranged in rear of the foremost portions of the latter, and an intermediate plane arranged between the upper and lower planes and secured to the wings of the latter and having its forward portion disposed in rear of the forward portion of the lower plane and in advance of the upper plane.

2. In a flying machine a supporting surface comprising a lower plane having dihedrally angled wings, an upper plane extending between and secured to the wings of the lower plane, and a relatively shorter intermediate plane extending between and secured to the wings of the lower plane, said planes being arranged in stepped as well as superposed relation.

3. In a flying machine a supporting surface comprising a lower plane having wings inclined upwardly and outwardly and up-

wardly and rearwardly, an upper plane extending between and secured to the wings of the lower plane near their extremities, said 50 upper plane having its leading edge terminating in rear of the leading edges of the wings of the lower plane between the inner ends of the latter and such points of attachment of the upper plane thereto, and an 55 intermediate plane extending between and secured to the wings of the lower plane and having its leading edge arranged at a point in advance of the leading edge of the upper plane and on a line between the same and 60 the foremost portions of the leading edges of the wings of the lower plane.

4. In a flying machine, a frame including a car inclining upwardly and forwardly in advance of its transverse center and inclined upwardly and rearwardly in rear of its transverse center, a lower plane having wings secured to the forward portion of the car and inclined outwardly and upwardly and upwardly and rearwardly, a motor upon 70 the forward portion of the car between the wings of the lower plane and inclined to correspond to the inclination of such portion of the car, an upper plane extending between and secured to the wings of the lower 75 plane, an intermediate plane extending between and secured to the wings of the lower plane, the said several planes being arranged in stepped relationship, an aviator's seat mounted upon the rear inclined portion 80 of the car, longitudinally extending shafts upon the wings of the intermediate supporting surface and having a degree of inclination corresponding to that of the motor, gearing between said shafts and the motor, 85 and propellers upon said shafts operating in rear of the wings of the supporting planes.

In testimony whereof I affix my signature in presence of two witnesses.

ABRAHAM LINCOLN HENSON.
